UNITED STATES PATENT OFFICE.

HERMAN BURGI, OF SPRINGFIELD, MASSACHUSETTS, ASSIGNOR OF ONE-HALF TO
CHARLES H. TENNEY, OF HARTFORD, CONNECTICUT.

MEANS FOR DISTRIBUTING THE COMBUSTION OF GASES.

Application filed March 16, 1920. Serial No. 366,181.

To all whom it may concern:

Be it known that I, HERMAN BURGI, a citizen of the United States, and residing at Springfield, Hampden County, State of Massachusetts, have invented certain new and useful Improvements in Means for Distributing the Combustion of Gases, of which the following is a specification.

This invention relates primarily to means for so regulating and controlling the combination of gases entering a long flue or chimney at one end and passing along it to the other end so as to control and regulate the actual heating effect of the gases on the surrounding elements at the different points longitudinally of the flue. It was designed primarily for use in heating benches of retorts used in making coal gas and is shown in the drawings applied to that use, although it is not in its broader aspects limited in that respect. In making coal gas the retorts are usually arranged in tiers with vertical flue spaces between the adjacent tiers for the passage upward of flame and hot products of combustion to heat the retorts. Monoxide gas is generated below the flue and retorts and is discharged into the flue at the bottom with sufficient air to complete combustion. The actual combustion, however, does not extend very far up in the flue and since the burning or burned gases are giving up heat to the retorts which they pass they gradually lose their high temperature and heating effect and if the flue is too long will not at the upper end be hot enough to heat a retort to the necessary temperature in gas making. The result has been that the benches of retorts in coal gas making have usually been low with only a few superposed retorts so that each should receive sufficient heat. Aside from the necessity for sufficient heat for each retort it is very desirable from the standpoint of uniformity and quality of the product that the heating of all the retorts shall be as near uniform as possible and it has been difficult to heat the upper retorts properly without overheating the lower retorts where the combustion is all at the lower end of the flue. My invention provides means by which the combustion is distributed along the flue and is not all at the lower end and the heat is correspondingly distributed so as to heat all of the retorts to substantially the same degree. It furthermore permits

using a much higher tier of retorts than was possible heretofore and this is a result which has long been desired. This results in much economy in space, work and consumption of fuel and secures a more uniform and better product. The novel features will be apparent from the following description and claims taken with the drawings.

In the drawings:

Figure 1 is a cross section through a bench of retorts and gas supply; and

Figure 2 is a partial section on the center line of Figure 1 showing a series of flues for different benches receiving gas from the same source.

In the drawings, 10, represents the walls made of refractory material in the usual way constituting the furnace or combustion chamber for generating the hot gases. As is usual there is a grate 11 on which coke is placed below which the necessary steam and air are admitted to cause the necessary combustion to produce monoxide gas in the chamber 12. As is usual in such devices the chamber 12 extends along under a number of flues 13, 14, 15, which extend up between tiers of retorts and the gas in the chamber 12 enters these flues at the bottom. The retorts in each tier are ordinarily arranged as shown in Figure 1, the retorts 16 being placed one above the other on one side of the flue 13 and the retorts 17 are similarly placed on the other side. After the hot gases have passed up the flue 13 they pass over the top of the upper retorts and back down towards the bottom to an escape pipe, as is usual and well known in this art. Heretofore the practice has been to supply sufficient air to the bottom of the flue 13 at a point where the gases enter it from the chamber 12 to complete combustion and all of the combustion thus took place near the bottom of the flue where the air had access to all of the monoxide gas.

According to my invention the monoxide gas passes in a hot condition from the chamber 12 through a slot or passageway 18 to the discharge openings 19 and 20 into the bottom of the flue 13 and a part of those gases thus enter the flue at that point, but it will be observed that there is a pipe 21 in communication at its bottom with the passageway 18 and thus part of the monoxide gases instead of escaping through the openings

19 and 20 pass up to the upper end 22 of the pipe 21 and there enter the flue approximately opposite the third tier of retorts. Air enters through the walls 10 through 5 vertical slots 23 and 24 on opposite sides but passes up through the passageways 25 and 26 where it is discharged into the bottom of the flue 18 adjacent the monoxide gas which is entering through the openings 19 10 and 20. The air inlet openings are sufficiently large to supply more air than is necessary to complete combustion of the gas which enters through the openings 19 and 20 and which is sufficient to cause and complete the 15 combustion of the additional supply of gas which is admitted to the flue part way up at the end of the pipe 22. It will be observed therefore that combustion takes place not merely at the bottom of the flue but also at a 20 point selected above the bottom so as to distribute the actual combustion longitudinally of the flue. Sliding dampers 27 and 28 may be used to regulate the discharge of air and gas at the bottom of the flue and a side 25 valve 29 may regulate the amount of gas passing up through the flue 21. These valves or dampers permit control of the combustion so as to regulate the heat as desired as between the bottom and the upper portion of 30 the flue. It will be understood that while I have shown only one point above the lower end where additional combustion is produced, my invention in its broader aspects is not limited in this respect. I find, however, that 35 this one additional point for combustion enables me to use benches of retorts including as high as eight superposed retorts.

Having thus described the invention what is claimed as new and desired to be secured 40 by Letters Patent is:

1. In a device for causing and properly distributing the heat of combustion of gases, the combination with an elongated combustion chamber, of a series of elements successively at the sides or walls of said chamber to be heated with substantial uniformity from combustion in said chamber, means for supplying a combustible gas to one end of said chamber and burner mechanism for 45 there discharging some of said gas into said chamber, means for supplying materially more air to said chamber at said burner mechanism than necessary to support the resulting combustion, means for conveying a 50 part of said combustible gases to a point removed longitudinally of the chamber from said burner mechanism and there so discharging said gas into said chamber as to cause combustion with the surplus passing air

thus distributing the combustion and resulting heat along the chamber. 60

2. In a device of the class described, the combination with an elongated vertical combustion chamber, of a series of heat absorbing elements at successive elevations along 65 it, means for supplying a combustible gas to the lower end of said chamber to burn therein, means for supplying an excess of air to the lower end of said chamber adjacent the gas inlet, and means for supplying additional combustible gas to said chamber considerably above its lower end thus distributing the combustion and heat along the chamber. 70

3. In a device of the class described, the 75 combination with a vertical flue or chamber, means for supplying to and discharging into said chamber at its bottom a gaseous mixture containing hot monoxide gas, means for admitting to said chamber adjacent the entering gas more air than that necessary to complete the combustion of the gas, and means for conveying a gaseous mixture containing hot monoxide gas from the bottom up substantially through the combustion 80 zone and there discharging it into the upwardly passing current of air and products of combustion to cause additional combustion. 85

4. In a device of the class described, the 90 combination with a bench of retorts for making coal gas arranged in tiers with a long vertical combustion flue between them, means for generating and supplying to the bottom of said flue hot gases containing 95 monoxide gas, burner mechanism for admitting part of said gases to said flue at the bottom, pipe mechanism for conveying a part of said gases up said flue part way to the top and there discharging them into the 100 flue, means for admitting sufficient air at the bottom of said flue to cause complete combustion of the gas there admitted as well as that admitted at the higher elevation.

5. In a device of the class described, the 105 combination with a vertical flue or chamber, of means for discharging into said flue at the bottom a gaseous mixture containing hot monoxide gas for combustion, pipe means for conveying a gaseous mixture containing 110 hot monoxide gas from the bottom of said chamber a material distance towards the top, and there discharging it into the chamber, and means for supplying air to said chamber to cause combustion at and beyond the 115 points where the gas is admitted.

In testimony whereof I affix my signature.
HERMAN BURGI.
